UNITED STATES PATENT OFFICE.

ARTHUR J. NILES, OF LANCASTER, NEW HAMPSHIRE.

PORTABLE WATER-CLOSET.

SPECIFICATION forming part of Letters Patent No. 449,426, dated March 31, 1891.

Application filed August 5, 1890. Serial No. 361,139. (No model.)

To all whom it may concern:

Be it known that I, ARTHUR J. NILES, a citizen of the United States, residing at Lancaster, in the county of Coos and State of New Hampshire, have invented certain new and useful Improvements in Portable Water-Closets; and I do hereby declare the following to be a full, clear, and exact description of the invention, such as will enable others skilled in the art to which it appertains to make and use the same.

My present invention contemplates an improvement over the portable water-closet shown and described in my former application, filed May 2, 1890, Serial No. 350,278, the object in view being to simplify and cheapen the construction and produce a more efficient and easily-operated arrangement of parts.

With these ends in view the invention may be said to consist in the peculiar features of construction and combinations of parts more fully described hereinafter, and pointed out in the claims.

Referring to the accompanying drawings, Figure 1 represents a vertical central section through the complete structure, showing the parts in their normal position; Fig. 2, a similar view showing the position of the parts after use, and Fig. 3 a top view or plan with the cover removed.

I first provide a base 2, which consists of a pail or receptacle, preferably circular in form and provided with a top 3, having at its center a hinged cover or lid 4, which opens downward into the receptacle and is kept normally closed by a suitable spring 5, secured to said top 3 and bearing at its free end against said lid. This top is also provided with another hinged lid 6, arranged at or near its periphery and adapted to open out and form an orifice through which the contents of the pail 2 can be emptied. The upper edge of the latter extends above the top 3 and forms a flange or rabbet 7, within which fits a corresponding flange 8, formed by the lower portion of the upper or water pail or receptacle 9, which is of similar form to the lower pail 2 and has a bottom 10, which, it will be seen, is somewhat elevated from the top 3 of the lower receptacle to leave a space for containing the hopper basin or trap.

From the center of the bottom 10 of the pail 9 is erected a stand-pipe or tubular guide or socket 11, which opens out of said bottom and also has an open upper end. 55

The hopper is of the usual form, consisting of the bowl 12, vertical pipe or tube 13, leading downwardly therefrom, and the lateral annular flange 14, extending from said bowl and formed integral therewith. This hopper 60 is contained within the pail 9, and its lower end—*i. e.*, the pipe 13—fits within and telescopes with the stand-pipe 11, having sliding movement therein.

The receptacle 9 is covered by a top 15, having a suitable central opening 16 over the hopper and an annular depending flange 17, fitting within the upper end of said receptacle, and the hopper is connected to this cover or top by means of a circular band or strip 18 65 of suitable flexible material—such as rubber, canvas, or the like—connecting the outside edge of the flange 14 of the hopper-bowl and the inside of the band or flange 17 depending from the cover 15, and this connecting-web 70 forms a flexible hinge, which is also air-tight.

The water-pail is further rendered air-tight by means of a ring 19, fitting snugly over the upper end of the stand-pipe 11, and a flexible webbing 20, of conical or funnel-like form, 80 connecting said ring and the lower surface of the hopper-bowl 12, thus preventing the escape of air between the telescoping tubes, and on account of its flexibility maintaining this air-tight joint when the hopper is pressed 85 down, as hereinafter described.

Inside the conical webbing 20 are disposed suitable coil-springs 21, which fit between the upper surface of the ring 19 and the lower surface of the bowl 12, and thus act to keep 90 the latter in elevated position ready for use, and the former down tight upon the pipe 11. I also provide an arrangement for the introduction of fresh air, which consists of an inwardly-projecting tube 22, which opens out 95 of the depending flange of the cover 15, beneath the flexible webbing 18, and registers with an orifice 23 in the upper end of the receptacle 9. The inner end of this tube 22 is closed by a hinged lid 24, behind the projecting lower end of which is disposed a coil-spring 25, which is connected at its opposite

end to a lug 26, projecting from the tube, and acts to push the lid shut against the end of the latter. The upper end of this lid is connected by a flexible cord 27 to the under side 5 of the flange 14 of the hopper, and this connecting-cord is of such length that when the hopper is in its normal elevated position the lid will be held partially open against the pressure of the closing-spring 25. A water- 10 pipe 28 is secured at its upper end in the bowl 12, opening into the same, and thence extends down through the flange 14 and nearly to the bottom of the receptacle 9, its lower end also being left open.

15 The mechanism for operating the hopper consists of a forked lever 29, the diverging arms 30 of which extend on either side of the hopper and are pivotally connected thereto at its center. This lever has its fulcrum in 20 the lower end of a rigid arm 31, depending from the under side of the top or cover 15, and beyond this fulcrum on the end of the lever is attached an upright handle 32, which extends up through said cover and has on its 25 end a suitable knob 33, to be grasped in the hand. Beneath the lower end of the hopper-pipe 13 and in the space between the bottom 10 of the receptacle 9 and the top 3 of the bottom pail 2 is located a basin or trap 34, made 30 bowl-shaped and closing the lower end of the stand-pipe 11. A rigid arm 35 extends from the under side of this bowl and is pivoted to a stud or post 36, depending from the bottom 10, and the basin is held up against the pipe 35 by a spring 37, connecting the arm 35 and said bottom. It will be seen that this basin comes directly over the central lid 4 in the top of the pail 2.

When constructed as thus described, the 40 operation of my device is as follows: The cover 15 and connections—*i. e.*, the hopper and its appurtenances—are removed and the pail 9 filled with water, when the cover will be replaced with the hopper-tube 13, telescoping 45 with the stand-pipe 11, and the ring 19 fitting the latter. After using the closet the knob 33 is grasped and the lever pulled up, thus pushing down its forked end and with it the hopper, thus causing the cord 27, attached to the lid 24 of the air-inlet tube, to relax, when the spring 25 will close said air-tube and the receptacle 9 will become air-tight. It will now be seen that the pressure 50 of the flange 14 and webbing 18 upon the air 55 and water will cause the latter to be forced up through the pipe 28 and into the top of the hopper. The contents of the latter, together with the water, flow down its pipe 13, but in the meantime said pipe has been forced 60 down upon the basin 34, pushing the latter against the lid 4, and thus opening said lid into the lower pail 2. The basin is thus pushed down into said lower pail and empties into the latter, as seen more clearly in Fig. 2. 65 When the water has flowed through the hopper in sufficient quantity to thoroughly cleanse

it, the handle of the lever 29 will be released, when the springs 21 act to return the hopper to its raised position and the basin 34 and lid 4 will again close, being actuated by their 70 respective springs. When the hopper returns to its original position, it draws taut the cord 27, and thus the lid 24 of the air-pipe 22 is opened and a fresh supply of air enters the receptacle 9, when the closet is again ready 75 for use. Thus I provide a compact and portable water-closet, which can be very conveniently and easily employed with the best results.

It is evident that many slight changes which 80 might suggest themselves to one skilled in the art to which this invention relates could be resorted to without departing from the spirit and scope of my invention, and hence I do not wish to limit myself to the precise 85 construction herein shown.

Having thus described my invention, what I claim as new, and desire to secure by Letters Patent, is—

1. In a water-closet, the combination, with 90 a water-receptacle, of a vertically-movable hopper contained therein, a suitable connection between the hopper and the sides of the receptacle which renders that portion of the latter containing water virtually air-tight, and 95 an inlet-pipe leading from the water to the hopper, whereby the downward movement of the latter forces the water into its interior, as and for the purpose described.

2. In a water-closet, the combination, with 100 a water-receptacle, of a vertically-movable hopper contained therein, a flexible diaphragm connecting said hopper and the sides of the receptacle above the water contained in the latter, and an inlet-pipe leading from 105 the receptacle into said hopper, whereby the downward movement of the latter forces the water into its interior, as and for the purpose described.

3. In a water-closet, the combination of a 110 water-receptacle, a stationary guide within the same, a hopper consisting of a bowl and pipe leading therefrom, the latter fitting said guide, a lateral flange extending from the bowl of said hopper, a flexible connection between said flange and the inside of the water-receptacle, mechanism, substantially as described, for forcing said hopper and flange down upon the air and water in said receptacle, and a suitable inlet-pipe leading from 115 the latter into the hopper, as and for the purpose set forth.

4. In a water-closet, the combination of a water-receptacle, a stand-pipe within the same, a hopper consisting of a bowl and pipe 125 leading therefrom, the latter telescoping with said stand-pipe, a flexible connection between the bowl of said hopper and the inside of the water-receptacle, a similar connection between said bowl and said stand-pipe, mechanism, substantially as described, for forcing the hopper and connections down upon the 130

air and water in said receptacle, and a suitable inlet-pipe leading from the latter into the hopper, as and for the purpose set forth.

5. In a water-closet, the combination of a water-receptacle, a stand-pipe within the same, a suitable cover to said receptacle, a hopper consisting of a bowl and pipe leading therefrom, the latter telescoping with said stand-pipe and the former being provided 10 with a lateral flange, a flexible connection between said flange and said receptacle-cover, a ring fitting over the upperend of said stand-pipe, a flexible connection between said ring and the hopper-bowl, a pipe leading from the 15 latter to the lower part of the water-receptacle, a lever operating to force the hopper and connections down upon the air and water contained in said receptacle, and springs disposed beneath said hopper and arranged 20 to return the latter to its normal position, as set forth.

6. In a water-closet, the combination of a water-receptacle, a vertically-movable hop-

per contained therein and arranged to be forced down upon the air and water in said 25 receptacle, a fresh-air tube opening out of the latter and closed at its inner end by a spring-actuated lid, and a flexible connection between said lid and the hopper, whereby the former is automatically opened, as and 30 for the purpose described.

7. In a water-closet, the combination of a water-receptacle, a vertically-movable hopper contained therein and arranged to be forced down upon the air and water in said 35 receptacle, and a basin or trap hinged to the bottom of said receptacle and closing the lower end of said hopper, said basin arranged to be tipped by said hopper in its downward movement, as set forth. 40

In testimony whereof I affix my signature in presence of two witnesses.

ARTHUR J. NILES.
